EARTH MOVING DEVICE

Vern L. Schield, Waverly, Iowa

Application February 26, 1944, Serial No. 523,998

3 Claims. (Cl. 214—138)

1

This invention relates to earth moving devices and has particular reference to an excavating, dirt moving and material handling device.

While many devices of the excavating shovel type have been proposed for large scale earth moving, such devices have been for the main part large, heavy, especially designed and constructed machines which are notoriously expensive to buy and maintain.

It is a particular object and an important object of my invention to provide a small machine constructed of readily available units and parts which, by reason of their use for other purposes, are low in first cost and maintenance, so as to make available to the public a low cost machine which is relatively light and small but which can nevertheless do many of the common excavating jobs for which the large machines are too expensive to operate.

Still another object of my invention is to provide a machine adapted to be mounted on any ordinary conventional long wheel base truck chassis so as to eliminate the necessity for a special built truck or heavy expensive caterpillar-type tractor or carrier.

Still another object of my invention is to provide a device which is readily adaptable for use with a large variety of attachments such as drag lines, cranes, ditching machines, trench hoes, excavating shovels and the like.

Still another object of my invention is to provide an extremely simple device which is constructed of relatively widely available parts and units so that repair may be quickly effected.

Other and further features and objects of the invention will be more apparent to those skilled in the art upon a consideration of the accompanying drawings and following specifications, wherein is disclosed a single exemplary embodiment of the invention, with the understanding, however, that such changes may be made therein as fall within the scope of the appended claims, without departing from the spirit of the invention.

In said drawings:

Figure 1 is a view in perspective of a device constructed according to one embodiment of my invention.

Figure 2 is a view, partly in side elevation and partly in section, of the turntable of the device shown in Figure 1.

Figure 3 is a plan view of the turntable of the structure shown in Figures 1 and 2.

Figure 4 is a view in section of the turntable and bull ring shown in Figures 2 and 3.

Figure 5 is a view, partly in section and partly in elevation, illustrating the turntable drive and the control means for controlling the swing of the turntable and the movement of the dipper stick, or other excavating means, and

2

Figure 6 is a view in elevation of a clutch fork for use with the clutches of the turntable swing mechanism.

Referring now more particularly to Figure 1; a device constructed according to my invention may be mounted on a mobile base such as the stripped chassis of a truck such as illustrated at 10. The device of course could be mounted on a tractor or the like in the manner I am about to describe.

In mounting the device on the rear of a truck I preferably employ a pair of H channels 11 and 12 secured to the upper faces of the side members of the truck frame to reinforce the members and to act as a means for securing the channelled ring 13 on the truck. This channelled ring is of particular importance and a considerable portion of the cost of manufacturing a device of this character is saved by utilizing an ordinary steel channel which is rolled into a ring. This ring thus provides not only a circular path on which rollers 24 roll but also provides a circular lip or flange 15 for the hook roller 151 to roll under to keep the machine from tipping.

To the inner face of the channel member 13 I secure an internal gear or bull gear 14. This gear is preferably bolted in place so that it can be replaced and this bull gear is readily available on the open market without the necessity of using a specially constructed and cut gear.

A rectangular frame having side members 16 and end members 17 is mounted for rotation about the axis of the bull gear by means of a through shaft, center pin or king pin 18.

The center pin 18 is rotatably mounted in sleeve bearings 19 and 21. The sleeve bearing 19 is secured to cross members 22 which are in turn secured to the channel member 13.

The bearing member 21 is secured to a cross member 23 which is in turn secured to the side frame members 16 of the turntable frame.

Rollers 24 are provided which are rotatably mounted in turntable frame stiffening members 26 and these rollers roll on the bull ring 13. A plan view of the various members just described is shown in Figure 3. The turntable frame 16 and 17 is thus free to rotate on the flange of the steel channel ring, and held in place by the king pin 18.

A power means, such as the internal combustion engine, illustrated at 30, is mounted on an engine frame 31 mounted above the turntable frame 16. The unit here illustrated is a hoist unit commonly used for elevating building material in erecting buildings, and includes two drums 35 mounted in side frame members 32, these drums being driven from the power unit 30 through a chain drive such as that enclosed in the housing 33. These units are provided with the drums 34 and 36 and the drum 36 has an extension shaft 37 projecting beyond the side of the frame which I utilize in rotating or swinging the turntable.

The means for rotating the turntable includes a sprocket 38, a chain 39, and sprockets 41, the sprocket 41 being mounted upon a cross shaft or swing shaft 42 in bearings 43, which in turn are secured on channel members 44.

The shaft 42 is provided with oppositely disposed clutches 46 and 47 and these clutches are connected through the links 48 to the control member 49 to be selectively engaged to rotate the turntable in one direction or the other as desired. Rotation of the turntable is effected through the bevel gears 51 or 52 which selectively drive the bevel gear 53 in one direction or the other to rotate the spur gear 54 in one direction or the other as desired. The spur gear 54 is in mesh with the bull gear 14 and since the shaft 56 on which the spur gear and bevel gear are mounted is rotatably mounted in a bearing 57 on the turntable frame, rotation of the turntable in one direction or the other as desired is secured. A clutch fork 50 is shown in Figure 6 by which the clutch collars 55 are shifted.

An A frame or boom 61 is pivotally mounted on the end of the turntable frame opposite to the power unit 30 by means of pins 62 and projects outwardly therefrom.

I preferably mount a mast structure on the turntable frame by means of the A shaped sheave support frame 63, the mast members 64, 66, struts 67 and 68, and tension members 69 and 71. This structure is stiffened by the cross members 72.

The sheaves 34 and 36 are geared together as by gears (not shown) and these sheaves may be engaged to their respective drive shafts by means of clutches indicated at 73 and 74. If the clutch 74 is engaged the sheave 34 is rotated and the A frame may be raised or lowered by means of the cable 76 which is reeved over the cat-head sheave 77, the boom head 78, and dead ended on the boom or A frame 61.

If the clutch 73 is engaged, the drum or sheave 36 is rotated in one direction or the other to either reeve in the line 79 or let it out to thus swing the stick 81 which is pivotally mounted on the end of the boom 61. The dipper stick 81 may carry the ditching bucket 82 or a conventional excavating shovel. The clutches 73 and 74 are controlled by means of control handles 83 and 84 through any suitable linkages as shown. Foot pedals 85 may be utilized for braking the sheaves 34 and 36.

Obviously since two lines are available, a crane may be mounted in the place of the A frame 61 and one line used to raise and lower the boom and the other line used to raise and lower a load. In the same manner a drag line may be rigged up and operated from the structure here shown. The entire turntable may be rotated as desired, so that a load may be picked up and loaded in the wagon or truck or disposed in a pile as desired.

It is apparent that I have provided a machine which may be moved from one job to another at a minimum of expense and time. This effects a material saving in the overall cost of a job and permits the machine to accomplish many small jobs or operations in a short time. The extreme outstanding simplicity and the structure of the machine permits ready and quick servicing and repair of parts and substitution of attachments. The parts are easy to get at for repair and servicing. The swinging clutches may be mounted or dismounted in a few minutes. This machine is extremely light, which also makes it highly portable, and the operator can quickly change from one attachment to another. A ma-

chine constructed according to my invention permits mounting of the operating machinery well back of the center of gravity so that the need for dead counterweights is eliminated and the machinery itself acts as a live counterweight.

Although I have described a specific embodiment of my invention, it is apparent that modifications thereof may be made by those skilled in the art. Such modifications may be made without departing from the spirit and scope of my invention as set forth in the appended claims.

I claim as my invention:

1. In an earth working device of the character described, a truck having a rear axle and rear supporting and driving wheels, and a chassis frame, a turntable mounted on the rear of said frame substantially over the rear axle and including a forwardly extending frame, an elevator hoist unit mounted on the forward end of said turntable frame, a boom pivoted at its inner end to the rear end of said turntable frame and extending generally rearwardly, a mast structure fixedly carried at the rear end of said turntable frame and extending substantially directly upwardly therefrom and generally above said rear axle in substantially all positions of said turntable, and cable means extending between said hoist and boom and trained over the upper end of said mast structure.

2. In an earth working device of the character described, a truck having a rear axle and a chassis frame, a turntable mounted on the rear of said frame substantially over the rear axle and including a forwardly extending frame, an elevator hoist unit having two driving drums and mounted on the forward end of said turntable frame, a boom pivoted at its inner end to the rear end of said turntable frame and extending generally rearwardly, a mast structure carried at the rear end of said turntable frame and extending substantially directly upwardly therefrom generally above said rear axle in all positions of said turntable, a first cable means extending between said hoist unit and boom and trained over the upper end of said mast structure, and a second cable means extending directly from said hoist unit to a dipper stick carried by said boom, one of said cable means being connected with one of said driving drums and the other cable means being connected with the other of said driving drums.

3. In an earth working device of the character described, a truck, a turntable mounted generally over the rear wheels thereof and including a forwardly extending frame, an elevator hoist unit mounted on the forward end of said turntable frame, a boom pivoted at its inner end to the rear end of said turntable frame and extending generally rearwardly therefrom; a mast structure including an A frame extending substantially vertically from the rear end of the said turntable frame, a freely rotatable sheave mounted in the upper portion of said A frame; a bracing structure for the A frame including struts mounted, at their lower ends adjacent the lower ends of the A frame and diverging upwardly and forwardly away from the A frame and the struts, and tension members extending from the upper ends of the struts forwardly and downwardly to the forward end of the turntable; and a cable extending between said hoist and said boom and trained over the said sheave.
